SHUTTLE-BOX TENSION-CONTROLLING MECHANISM FOR LOOMS.

Application filed August 23, 1922. Serial No. 583,781.

To all whom it may concern:

Be it known that I, CLARE H. DRAPER, a citizen of the United States, residing at Hopedale, in the county of Worcester and 5 State of Massachusetts, have invented certain new and useful Improvements in Shuttle-Box Tension-Controlling Mechanism for Looms; and I do hereby declare the following to be a full, clear, and exact description 10 of the invention, such as will enable others skilled in the art to which it appertains to make and use the same.

The present invention relates to an improvement in shuttle box tension controlling 15 mechanism for looms.

The object of the invention is to provide means for applying variable resistance to the entrance of the shuttle into the shuttle box. To this end the present invention consists in the mechanism hereinafter described 20 and particularly defined in the claims.

In the accompanying drawings illustrating the preferred form of the invention, Fig. 1 is a side elevation of a portion of a loom 25 showing the picker stick check; and Fig. 2 is a rear elevation of a portion of the lay showing the shuttle box, picker stick and picker stick check.

The illustrated embodiment of the invention 30 is described as follows: The loom frame 1, the lay 2, the shuttle box 3, the picker stick 4, the lay sword 5 and the pitman 6 may all be of the usual form. The check strap 10 consists of a strap of the usual form, both ends of which are secured to the strap support 11 by means of the bolt 12. The rear side of the strap is supported on the strap bracket 13. The bracket 13 is secured to the lay by means of bolts 14 and extends 35 below the lay and presents a surface against which the check strap is adapted to be pressed by the presser plate 15, which is supported upon the rearwardly extending lug 16 of the bracket 13, and held from lateral 40 movement by lugs 17 which are adapted to engage the upward extensions 18 of the bracket 13. The presser plate 15 is provided at its center with a boss 19 which receives the end of the presser rod 20 to which it is 45 secured by means of the cotter pin 21. The rod 20 is supported at its rear end in a

bracket 22 attached to the frame of the loom through which it is adapted to reciprocate freely. The rod 20 is embraced by the presser spring 23, which bears at its front 55 end against the boss on the presser plate and at its rear end is received in an adjustable spring cup 24 carried by the bracket 22. This spring cup 24 provides means for varying the tension of the spring and thereby 60 varying the pressure exerted by the presser plate on the check strap.

The lay is shown in Fig. 1 on the back center, at which time the presser plate 15 bears with maximum pressure upon the check 65 strap. If at this time the shuttle is received in the shuttle box the resistance of the check strap to movement in the friction device is produced by the presser device to the greatest extent to which it is possible with any 70 given adjustment. Then as the lay moves forward the pressure of the presser spring on the presser plate is diminished. With an early shuttle boxing the pressure is greatest, and as the shuttle boxing is delayed the 75 pressure on the presser plate is diminished.

The broad invention of a variable resistance to the boxing of the shuttle is not claimed herein, as it forms the subject matter of an application for Letters Patent 80 filed by Clare H. Draper July 11, 1922, Serial No. 574,212.

Having thus described the invention, what is claimed is:

1. Shuttle box tension controlling mechanism for looms having, in combination, a lay, a shuttle box, a check strap, a friction device acting on the check strap to retard its motion, yielding means acting on the friction device with varying pressure depending 85 upon the position of the lay to increase the pressure as the lay approaches the back center, and to decrease the pressure as the lay recedes therefrom.

2. Shuttle box tension controlling mechanism for looms having, in combination, a lay, a shuttle box, a picker staff, a friction device acting on the picker staff to retard its motion during the time the shuttle is entering the box, and yielding means acting 100 on the friction device with varying pressure depending upon the position of the lay to

increase the pressure as the lay approaches the back center, and to decrease the pressure as the lay recedes therefrom.

3. Shuttle box tension controlling mechanism for looms having, in combination, a lay, a shuttle box, a friction device acting on a part having operative connection with

the shuttle to retard its motion, yielding means acting on the friction device with varying pressure depending upon the position of the lay to decrease the pressure as the lay moves forward. 10

CLARE H. DRAPER.
